UNITED STATES PATENT OFFICE.

HANS MANGOLD, OF FURTH, GERMANY.

DESIGN FOR A LANDSCAPE TOY.

Application filed March 25, 1926. Serial No. 17,048. Term of patent 3½ years.

To all whom it may concern:

Be it known that I, HANS MANGOLD, a citizen of Germany, residing in Furth, Bavaria, Germany, have invented a new, original, and ornamental Design for Landscape Toy, of which the following is a specification, reference being had to the accompanying drawing, forming part thereof.

The figure is a perspective view of a landscape toy showing my new design.

I claim:

The ornamental design for a landscape toy as shown.

In testimony whereof I have affixed my signature to this specification.

HANS MANGOLD.
